UNITED STATES PATENT OFFICE

1,928,914

ODORLESS GARBAGE DEVICE

Joseph C. Sparrow, Cleveland, Ohio

Application August 18, 1930. Serial No. 475,998

3 Claims. (Cl. 220—44)

This invention relates to a portable garbage device and more particularly its object is to afford a substantially odorless garbage device adapted for receiving refuse and permit the dissipation of the gases of fermentation from the refuse.

Other and further important objects of this invention will be apparent from disclosures in the drawing and specification.

10 The invention in a preferred embodiment thereof is illustrated in the accompanying drawing and hereinafter more fully described.

On the drawing:

15 Figure 1 is a sectional elevation illustrating the arrangement of the parts of this novel odorless garbage device.

Figure 2 is a reduced front elevation illustrating a garbage device embodying the features of this invention.

20 Figure 3 is an enlarged plan view with the cover removed.

Figure 4 is a reduced top plan view of the cover.

25 Figure 5 is a reduced bottom plan view of the cover.

As shown on the drawing:

An outer container 11 is supported on three substantially equidistantly spaced legs 10, and the bottom portion 12 near its periphery is provided with a plurality of apertures 13 opening into the container 11. The top portion of the container 11 is folded back upon itself as indicated at 14 or otherwise reinforced to provide a stiffened rim portion for receiving a cover 15.

30 The metal cover 15 has a downwardly extending flange 16 adapted to receive and to frictionally engage the top folded portion of the container so as to provide a comparatively tight fitting cover for the container.

40 An embossed or slightly raised center portion 18 of the cover is provided with a central opening 19, and an upwardly extending tubular stack or draft pipe 20 having a transverse screen 24 for excluding insects and the like from the interior of the container 11.

45 A conical shield 23 is elevated above and secured to the upper end of the draft pipe for excluding rain, snow and the like from the interior of the container while permitting free outflow of air. A handle 25 secured to the top portion of the conical protecting shield facilitates the placing upon and removal of the cover to or from the container.

50 A removable garbage receptacle 26 of the conventional type, supported by the bottom plate

12, is so disposed within the container 11 to provide air circulating chambers 17 and 21. A bail or handle 27 having supporting brackets 29 rests on the top of the receptacle for facilitating the insertion and removal of the receptacle to and from the container.

The operation is briefly as follows:

The cover 15 of the garbage container is removed from the top of the container 11 and the garbage is deposited in the receptacle 26. The 65 cover 15 is then replaced.

The circulating air flows through the apertures 13 into the lower portion of the container 11, passing upwardly in the chamber 17 between the walls of the containers and receptacle. The upflowing 70 air is drawn into the chamber 21 where it mixes with gases, if any, arising from garbage in the receptacle 26, and is dissipated through the draft pipe 20 to the atmosphere.

It is to be noted that the combined area of the 75 apertures 13 permit the admission in the chamber 21 of a large volume of air, thus diluting and purifying any gases to such an extent that when discharged through the draft pipe into the atmosphere it is substantially odorless.

80 The transverse screen 24 excludes insects from the garbage contained in the receptacle 26. The elevated protecting shield 23 excludes rain, snow and the like from the interior of the container, while permitting free outflow.

85 Of course, it is to be understood that although the invention is illustrated and described in detail in a single embodiment thereof, the invention is not to be thus limited, but only in so far as defined by the scope and spirit of the appended 90 claims.

The invention is claimed as follows:

1. A receiver for garbage comprising a container having a bottom with a plurality of apertures for the admission of air, a rigid receptacle 95 disposed in said container with its sides spaced from the sides of the container and arranged to enable the air entering said apertures to pass between said receptacle and container, a removable cover tightly fitting said container and having an 100 opening centrally disposed of the upper end of said receptacle, a draft pipe secured to said cover and communicating with said opening to cause the air entering said apertures to pass over the upper end of the receptacle before exit, and means 105 for shielding the upper end of said pipe against the entrance of rain.

2. A receiver for garbage comprising a container having a bottom with a plurality of apertures for the admission of air, a receptacle of rigid 110

material within said container with its sides spaced from the sides of the container to form an air passage, means to support said receptacle with its bottom spaced above said apertures to enable free passage of air therethrough at all times, and a ventilating cover for said container having parts so arranged that air entering said apertures will be drawn over the top of said receptacle.

3. A receiver for garbage comprising a container having a bottom with a plurality of apertures for the admission of air, a receptacle of rigid material within said container with its sides

spaced from the sides of the container to form an air passage, a bottom for said receptacle having its peripheral margin downwardly deflected to define a support, whereby the bottom of the receptacle is maintained spaced above said apertures to enable free passage of air therethrough at all times, and a ventilating cover for said container said apertures and cover cooperating to cause a flow of air between the casing and over the top of said receptacle.

JOSEPH C. SPARROW.
